UNITED STATES PATENT OFFICE.

FRANK M. MOORE, OF SYRACUSE, NEW YORK.

IMPRESSION-ROLLER.

SPECIFICATION forming part of Letters Patent No. 468,071, dated February 2, 1892.

Application filed April 2, 1891. Serial No. 387,393. (No model.)

To all whom it may concern:

Be it known that I, FRANK M. MOORE, of 5
Syracuse, in the county of Onondaga, in the
State of New York, have invented new and
useful Improvements in Impression-Rollers,
of which the following, taken in connection
with the accompanying drawings, is a full,
clear, and exact description.

This invention relates to the class of im- 10
pression-rollers which are employed in the
manufacture of moldings having their sur-
faces formed of plastic material, by means of
which rollers the required embellishment is
impressed in the surface of the molding while
15 in a plastic state.

The object of the invention is to produce
said impression-rollers in an inexpensive man- 20
ner and at the same time impart to them the
requisite stability and durability and also
perfect accuracy and harmony in the repeated
parts of the embellishment intagliated in the
surface of the roller; and to that end it con- 25
sists in the novel construction and combina-
tion of parts hereinafter described, and set
forth in the claims.

In the annexed drawings, Figure 1 is a face
view of the impression-roller in its operative
position. Fig. 2 is an end view of the same.
Fig. 3 is a longitudinal section on line $\alpha\alpha$,
30 Fig. 2; and Fig. 4 is a detached perspective
view of one of the sectors of the impression-
roller.

Similar letters of reference indicate corre- 35
sponding parts.
R represents the impression-roller, which is
usually mounted on a horizontal shaft s , which
is journaled at opposite ends on suitable sup-
ports not necessary to be shown. A carry- 40
ing-roller R' is arranged under said impres-
sion-roller to support the molding m , which is
passed longitudinally between said rollers, as
represented in dotted lines in Fig. 1 of the
drawings, to receive the impression from the 45
roller R . Said impression-roller has usually
been formed in one piece of metal, and the
ornamentation which is to be produced on the
face of the molding was engraved or stamped
in the surface of the roller, and in some cases 50
such impression-rollers have been provided
with design-plates detachably connected to

the convex surface of the roller and were em-
ployed for marking designs upon cement pave-
ments or walls. Such a construction is very
expensive and the accuracy and harmony of
the repeated parts of the ornamentations are 55
very difficult to be obtained. To obviate these
defects I form the body of the impression-
roller R of three or more separate sectors
 $a a a$. In the majority of cases I divide said
roller into four sectors, as shown, and firmly 60
unite the same by means of suitable ties.
Each of these sectors has intagliated directly
on its exterior a section of the continuous or-
namentation to be applied to the molding m .
In constructing said roller I form a pattern 65
of one of the sectors a , and then mold and
cast therefrom of suitable metal the desired
number of roller-sectors. Said pattern being
formed of wood allows the ornamentation to
be easily carved in the convex face of the 70
sector-pattern, and inasmuch as all the sectors
are cast from one and the same pattern it is
obvious that the consecutive portions of the
ornamentation must be fac-similes and in per-
fect harmony in their sequential arrangement. 75
To firmly unite the sectors $a a a a$, I prefer-
ably form each with a transverse groove b and
with rabbets $c c$ on opposite ends, which
groove and rabbets intersect those of the ad-
jacent sectors. The number of sectors re- 80
quired to form a roller I tie together by in-
serting solid metallic rings $t t t$ in the groove
and rabbets and then drilling longitudinally
through the united sectors at such points as
to form holes through the aforesaid rings and 85
intervening portions of the sectors, into which
holes I insert bolts or rivets $d d$, as shown in
Fig. 3 of the drawings.

I find that the simplest and most conven-
ient manner of tightly fitting the rings $t t t$ 90
in the groove and rabbets consists in pouring
melted white metal or Babbitt metal into the
into the central eye e of the combined sectors
sufficient to fill the groove and rabbets and
then drilling out the metal contained in the 95
central eye e .

Having described my invention, what I
claim as new, and desire to secure by Letters
Patent, is—

1. The improved impression-roller composed 100

of sectors intagliated externally and each having in its inner portion a transverse groove intersecting those of the adjacent sectors and a metallic ring seated in the grooves of the 5 combined sectors, as set forth.

2. An impression-roller composed of the sectors $a a a a$, each formed with the groove b and rabbets $c c$, and the metallic rings $t t t$, filling jointly the grooves and rabbets of the 10 combined sectors, as set forth.

3. An impression-roller constructed of the sectors $a a a$, each formed with the groove

b and rabbets $c c$, the metallic rings $t t t$ in said groove and rabbets, and the bolts or rivets $d d d d$, passing through the said metallic 15 rings and intervening portions of the sectors, substantially as described and shown.

In testimony whereof I have hereunto signed my name this 7th day of March, 1891.

FRANK M. MOORE. [L. S.]
